UNITED STATES PATENT OFFICE.

CONSTANTINE B. VOYNOW AND GEORGE B. TAYLOR, OF PHILADELPHIA,
PENNSYLVANIA.

RAILWAY.

976,708.

Specification of Letters Patent. Patented Nov. 22, 1910.

Original application filed December 6, 1907, Serial No. 405,445. Divided and this application filed August 22, 1910. Serial No. 578,425.

To all whom it may concern:

Be it known that we, CONSTANTINE B. VOYNOW and GEORGE B. TAYLOR, citizens of the United States, residing at Philadelphia, county of Philadelphia, and State of Pennsylvania, have invented certain new and useful Improvements in Railways, of which the following is a specification, reference being had therein to the accompanying drawing.

10 Our invention relates to railways and has for its object the production of an improved system and methods of operation therefor.

Standard railway practice in practically all the countries of the world has now for 15 many years prescribed the use of flanged wheels running upon inverted T rails. This type of rail has a flat or round head or tread portion, a relatively deep web which becomes deeper as the weight of metal and the weight 20 of rolling stock increases, and a broad foot. Considerable variation in tread section has arisen, and many special forms of rolls have been devised, by reason of the widely varying conditions met with in urban, interurban 25 and long distance hauling; but the flanged wheel remains substantially the same under all conditions, its only variation being in the depth or thickness of the flange and the angle or width of the tread. For interurban and 30 trunk lines where high speeds are necessary, heavy construction and relatively deep flanges are employed of necessity, and in such case the head of the rail has a plain section which has become familiar in all steam rail-

35 way construction. Where interurban or other outside lines are connected directly with city lines, that is to say where high speed and relatively low speed lines are joined, it is necessary to employ the high or low speed 40 rails throughout if the same wheels are to run over both portions of the system. In local traction lines the tread of the rails is usually on the outside, but a tram or lateral flange is rolled below the inside of the tread 45 so as to form a slot to take the wheel flanges.

Of course this slot may vary in depth to a considerable extent without changing the character of the rail, but because of the necessity of keeping the slot clear of obstructions, it is usually made shallow, and of a very wide V-shape, the tram in fact sloping down from the horizontal to an angle of perhaps 70 or 80 degrees with the inner face of the head or tread. If deep wheel flanges are

to be accommodated so that interurban cars 55 can pass over city lines, this slot on the rail head must be deepened, with obviously attendant disadvantages.

According to our present invention, we obviate all the disadvantages heretofore experienced, where different parts of a system or different communicating roads carry different classes of travel, for example local and interurban, with the necessity for one class to penetrate into the territory of the other, as for example interurban traffic to pass over the rails of the local street railway.

Stated very briefly our invention comprises a railway system in which the rolling surface is a uniform unbroken plane surface throughout the entire system, including the straight rails which for heavy traffic are of T section, frogs, switches, crossings, etc.; and in order to accommodate different classes of traffic and different parts of the system, 75 that is to say cars traveling at different speeds or the like, we protect the rails by means of lateral guiding flanges which for the low speed portions may be low and for the high speed or heavy traffic portions are 80 made relatively high and heavy.

Our present invention is a division of our prior application filed December 6, 1907, Serial No. 405,445, in which we claim the system broadly.

Our invention is illustrated in the accompanying drawings in which—

Figure 1 is a side view of a junction or meeting point between the rails of urban and interurban or long distance lines of the type shown in our parent case, showing the difference in rail flanges. Fig. 2 is a section taken on the line 2—2 of Fig. 1. Fig. 3 is a section taken on the line 3—3 of Fig. 1. Fig. 4 is a section showing double flanged rails.

The rail R, which is shown in section in Figs. 2 and 3 has an extended vertical web r, a broad foot r', a head r² having a flat tread r³ directly over the web, and an up-rising flange r⁴ or r⁴⁰. The flange r⁴ is shown of a height adapted particularly to urban and other low speed lines. The flange r⁴⁰ is much higher, being adapted particularly to interurban or long distance traffic where high speeds are maintained, and for curves, viaducts or other exposed places where guard rails have heretofore been em-

ployed. This flange r^{40} may be made as high as conditions require and we contemplate that its height will bear a definite normal relation to the weight of the metal in the rail. In other words, heavy high speed traffic demands heavy rails with high flanges. We always make the height of the tread from the bottom of the foot standard for all rails, so that the long distance or high speed rails can readily be connected by the ordinary fish plates or in any other suitable manner to the low speed rails. A side view of such a connection is shown in Fig. 1, the flange r^{40} on the high speed rail having approximately twice the height of the flange r^4 on the low speed rail. The treads, however, it will be observed, are continuous, so that the constant and unbroken level of the rail surface is maintained.

It will be noted that we carry the rail flange on the inside of the rail, so that the guiding pressure is on the inner faces of the wheels. Divers reasons exist for this construction, some of which are very important. One end accomplished is the crowning up of the street or other way upon which the rail is laid up to or above the level of the rail flange if desired. Another is the better location of base lines on curves and the like. Where the rail resistance is all on the outside rail, as it is with the ordinary construction, it will be found that there is a tendency to turn with the outside rail as an axis, so as to throw the load over outwardly. Thus even if the wheel flanges hold, there must be critical speeds at and beyond which a train would be necessarily derailed, while below these speeds great uncertainty exists because of the enormous strains brought upon the outside wheel flanges and the outside rail.

According to our present invention, and with the flange on the inside of the rail, we have two courses open to us in constructing a curve. Should we conclude to use our standard rail, which we might safely do within limits, we would gain considerable over the ordinary construction because the resistance to the derailing tendency is exerted on the outside faces of the inside wheels. The axis of any turning moment is

therefore shifted at once from the outside rail to the inside rail, and practically the only thing that can produce derailment is the breakage of a wheel or rail.

On sharp curves or those intended for high speed traffic, we prefer to use grooved rails similar in section to those in Fig. 4. Each rail in this case has double flanges, so that the strain is divided between the inner and outer rails, and the danger from any breakage of either rail is correspondingly lessened. We believe that with this construction the present guard rails in many instances can be dispensed with, although conservative practice would dictate their retention even with this construction in some cases. We also in some cases reverse the outside rail, which doubles the flange resistance using standard rails.

Having thus described our invention what we claim and desire to secure by Letters Patent is:

1. A railway system comprising lines of rails with a continuous unbroken uniform flat rolling surface and lateral guiding flanges integral with their heads, said flanges varying in height at different points in the system according to the requirements of the traffic thereover.

2. A railway system comprising high speed and low speed sections, each section equipped with rails having a continuous unbroken uniform flat rolling surface and lateral flanges integral with their heads, said rolling surfaces being connected at the same level and said flanges being at different heights approximately proportional to the speeds.

In testimony whereof I affix my signature in presence of two witnesses.

CONSTANTINE B. VOYNOW.
